ATTORNEYS.

UNITED STATES PATENT OFFICE.

HIRAM D. LAYMAN, OF BENTON, ARKANSAS.

COTTON-CHOPPER.

SPECIFICATION forming part of Letters Patent No. 296,700, dated April 8, 1884.

Application filed January 25, 1884. (No model.)

To all whom it may concern:

Be it known that I, HIRAM D. LAYMAN, of Benton, in the county of Saline and State of Arkansas, have invented a new and useful Improvement in Cotton-Choppers, of which the following is a full, clear, and exact description, reference being had to the annexed drawings forming part of this specification.

This invention relates to cotton-choppers having revolving holes; and the invention consists of the novel construction hereinafter described and claimed.

In the drawings, Figure 1 is a plan view of my improved cotton-chopper. Fig. 2 is a side elevation of the same, partly broken away; and Fig. 3 is an end view of the revolving hoes.

A indicates a wheeled frame having a pair of adjustable scrapers, B, at the front, and four plows, C, at the rear. Near the center of the frame is a longitudinal shaft, D, supported in oscillatory hangers, E E', and having a bevel-pinion, F, on its forward end gearing with a bevel-pinion, G, on the axle H. On this shaft is supported a drum, I, having a series of radial perforations, in which the shanks J of the hoes K are secured by set-screws L. The hoes are thus made readily removable, so that any desired number of hoes may be employed, according to the "stand" of cotton required. The hoes have slightly curved edges, as shown in Fig. 2, in order that they may not

cut the soil away from the roots of the cotton-plants left standing. The hanger E' serves also as a lever for swinging the shaft and its pinion to the rear, to throw the said pinion out of gear with pinion G, and it is provided with a rod, M, having shoulders N, for engaging with the cross-rod O, on which the handles P are supported. The shoulders N serve to hold the lever or hanger E' in either of two positions for holding pinion F either in or out of engagement with pinion G.

Q indicates a device for elevating the chopper to hold the plows and wheels out of contact with the ground when required.

The general frame-work shown in the drawings which is not claimed in this application is covered by my application No. 111,322, filed November 9, 1883.

What I claim is—
The combination, with the frame A and the shaft D, carrying the hoe-drum, and having bevel-pinion F, gearing with a pinion, G, on the supporting-axle of the frame, of the oscillatory hangers E E' and means for adjusting said hangers to hold the pinion F in or out of engagement with pinion G, substantially as shown and described.

HIRAM D. LAYMAN.
